UNITED STATES PATENT OFFICE

150,570

DESIGN FOR A SCYTHE

Henry L. Heineke, Springfield, Ill.

Application November 29, 1946, Serial No. 135,188

Term of patent 14 years

(Cl. D40—1)

To all whom it may concern:

Be it known that I, Henry L. Heineke a citizen of the United States, residing in the city of Springfield, county of Sangamon, and State of Illinois, have invented a new, original, and ornamental Design for a Scythe, of which the following is a specification, reference being had to the accompanying drawing, forming part thereof, and showing the design in front elevation in Figure 1, in side elevation in Figure 2, and in plan view in Figure 3.

I claim:

The ornamental design for a scythe, substantially as shown.

HENRY L. HEINEKE.
